UNITED STATES PATENT OFFICE.

OCTAIVE L. DESCHAMPS, OF PARIS, FRANCE.

MACHINE FOR CUTTING OUT TULLES, LACES, &c.

SPECIFICATION forming part of Letters Patent No. 244,985, dated August 2, 1881.

Application filed April 8, 1881. (No model.) Patented in France March 8, 1879.

To all whom it may concern:

Be it known that I, OCTAIVE LÉON DESCHAMPS, of Paris, in the Republic of France, have invented Improvements in Machines for Cutting Out Tulle, Laces, Valenciennes, Embroidery, Tarlatans, &c., from the webs on which they are manufactured, for which I have obtained Letters Patent of France for fifteen years, dated March 8, 1879, No. 129,494; and I do hereby declare that the following is a full and exact description thereof, reference being made to the accompanying drawings.

This invention relates to a new machine for cutting the edges of tulle, lace, valenciennes, and all articles of a similar nature into ornamental or other forms.

The invention consists in the new combination of parts hereinafter more fully described.

In the accompanying drawings, Figure 1 represents a front elevation of my apparatus. Fig. 2 is an end view of the same; Fig. 3, the transverse section (full size) of the working parts, the blade, and the roller. Figs. 4, 5, 6, and 7 show the blade complete and in detail, (natural size.) Figs. 8 and 9 show the handle for guiding the machine, (two-thirds size.) Finally, Fig. 10 shows a modification of the knife-moving mechanism.

The thread-cutting machine, Figs. 1 to 9, has its frame made of a steel-plate, *a*, or table supported by feet *a'* of suitable shape and dimensions, that are strengthened by bars *a''*. A cast-iron table, *b*, in size about like the plate *a*, is connected with and supported above the latter by two supports, *c c*. Between the supports *c* project from the table additional supports, *d d*, which form bearings for a shaft, *e*, carrying a tapering pulley, *f*. The shaft *e* hangs in line with the plane of the plate *b*, which is slotted to receive it, as indicated in Fig. 3. The table *a* carries blocks *a³* and *a⁴*, in which lies a shaft, *g'*, which carries at its inner end a cam, *g*, and at its outer end a grooved pulley, *g²*, as indicated in Fig. 1. The pulley *g²* receives motion from a pulley, *h*, keyed to the driving-shaft *h'*. The latter is hung in the framing *a'* of the machine. The shaft *h'* also carries a fixed pulley, *h²*, a loose pulley, *h³*, and at its inner end is provided with a crank, to which is connected the rod *p'* of the pedal *p*, so that the machine can be worked either by

power applied to the pulley *h²* or by the foot on the pedal *p*. On the shaft *h'* is also fixed a star-wheel, *I*, which, by a band or chain, communicates motion to a toothed wheel, *j*, mounted upon an intermediate shaft, *j'*. A pinion, *j''*, on the shaft *j'* gears into a toothed wheel, *k*, which, together with the tapering pulley *k'*, is hung loose on the shaft *a'*. The tapering pulley *k'* is in line with the pulley *f* above it, which it governs by a cord, which runs on one or other of the steps of said pulleys, according to the speed required. The supports *d d* also carry four guides, *l l*, in which fit two horizontal sliding rods, *l l*, both connected at their right-hand ends by a cross-piece, *m*, to which is pivoted one end of a horizontal rack, *n*, whose opposite end is guided in a mortise of a cross-bar, *n'*, that is carried by one of the supports *c*. In front of and in the same horizontal plane as this rack *n* is a rod, *o*, grooved throughout its length to receive and guide the handle-support or carrier *o'*, Figs. 8 and 9, said carrier *o'* having a handle, *M*, and a toothed crown-wheel, *o²*, that gears into the rack *n*, as indicated in Fig. 8. The carrier *o'* contains a vertical tube, *o³*, which carries the wheel *o²*, that is set in a recess of the carrier. The stem of the handle *M* is inserted into the lower end of the tube *o³*, and held in place by a couple of screws, as indicated in Fig. 9; but, if desired, the handle may be directly connected with the crown-wheel *o²*. By this arrangement the handle can be conveniently used to move the slides *l l* in or out at will.

The rod *o* is firmly secured in place, being held at one end in a projection, *l²*, of the support *d*, and at the other end in the cross-bar *n'*. The sliding rods *l l* carry collars *q*, each of which is perforated vertically for the reception of an upright rod, *r*, which I term the "blade-carrier" *r*. The blade-carrier *r* has up-and-down motion imparted to it by suitable connection with the cam *g*. The blade-carrier *r*, Fig. 3, is cylindrical, and has a screw-thread at its upper end, for the reception of a nut, *r'*. The upper end of the blade-carrier *r* is also made tubular, for the reception of the cutting device. This cutter has a base, *t*, of oval section, which base supports the blade *t'*, the same being a slender tapering spindle with rounded point. From the base *t* pro-

jects downward a stud, t^2 , fitted into a tubular socket, t^3 , that is held in place by the screw t^4 , as in Fig. 4. The spindle or blade receiver t' has a longitudinal groove for the reception 5 of the cutting-blade t^5 , Fig. 7. The cutting device is placed on the blade carrier r , and the socket t^3 is inserted and locked in the vertical cavity of the screw-threaded part of said rod. The blade t^5 participates, therefore, in all the 10 movements of the blade-carrier r , and is, moreover, able to turn in the socket t^3 around the axis of the blade-carrier r . By this rotary 15 movement, eccentric to blade-carrier r , I am enabled to compel the blade to always present its cutting-edge to the threads to be separated, whether they are coarse or fine, while the rounded edges of the spindle or blade-receiver t' guide the knife-edge so as to prevent its cutting the embroidery-threads or the 20 borders.

The tulle to be cut or edged is presented to the blade and fed along by rollers u and v . The roller u is mounted on the shaft e , and is covered with india-rubber or the like. The 25 roller v is above the roller u , being hung in a frame, v' , that is suspended from a goose-neck arm, x , of the frame-work by two spindles, v^2 , which pass through tubular screws v^3 , Fig. 3, that are secured in said goose-neck. The 30 latter is supported on the elevated table b . The screws v^3 contain within their cavities spiral springs that embrace the spindles v^2 and hold the frame v' down. Nuts v^4 serve to compress the said springs to the requisite extent. 35 By this means the regulation of the delivery of the band of material is effected, and may be made more or less energetic on one or other of its edges, according to the thickness of the design. In front of the two rollers u and v are 40 two others, y and z . The roller y is preferably of wood covered with india-rubber, or with roughened copper or other metal, and is hung in the plane of the table b , as shown in Fig. 3. The upper roller, z , is of metal, covered with 45 india-rubber, and turns in small blocks, that are attached to springs z' , which project from the frame v' . A sheet of metal, T , Fig. 3, tinted or colored white, black, or such other shade as agrees with the white, black, or other 50 colored ground of the tulle, is fixed in front of the roller u . It prevents fatiguing the eyes of the operator and allows him easily to follow the outline of the design.

The machine operates as follows: Having 55 set the machine in motion, the bands to be cut are placed between the rollers u and v , after having introduced them between the first rollers y and z by raising the latter. Fig. 3 shows the tulle in dotted lines. The operator guides 60 the delivery of the tissue with his left hand and takes the handle M in his right hand, giving it partial and successive rotations right and left, and vice versa, so that the cutting-tool, which is moved up and down by the cam 65 g , is at the same time moved horizontally backward and forward, according as the designs

are regular or irregular. The rollers v and y may also be covered with india-rubber, or roller v only. The bands of tulle or other material may, however, be guided by means of any suitable mechanism. 70

When the designs are regular or uniformly varied the backward and forward movement may be imparted to the slides $l l$ by aid of the mechanism represented in Fig. 10. As regards 75 the cutter, its up-and-down motion, and the delivery of the tissues no alteration occurs in the construction previously described, and the same letters of reference indicate like parts.

The shaft e , prolonged beyond the tapering 80 pulley f , bears the bevel-wheel A , which communicates motion to the pinion B , the axis of which bears the cone C . From this cone, by aid of the strap E , the motion passes to the parallel cone D . Above this latter the pinion D' is 85 fixed on the same axis. This pinion governs another, F' , by an intermediary endless chain. The pinion F' communicates with the axis of a cam, F , the bend of which receives through the sprungs G the contact of a roller, (not 90 shown,) such roller being carried by a rack, H , on which the two shafts $l l$ abut, which guide and govern the blade-carrier r .

The rack H' , guided in its case H^2 , is susceptible of rising and falling by turning the key 95 H^3 , which actuates it by a pinion. The roller carried by the rack can then rest on the cam at variable altitudes, and be moved backward and forward, more or less. Thus the horizontal backward-and-forward movement can be regulated according to the thickness of the design. 100

The cones C and D admit of increasing or decreasing the speed of the cam F —that is to say, render the horizontal backward-and-forward motion of the blade proportionate to the 105 delivery of the tissue or (which amounts to the same) proportions the movements with the spaces of the design. The strap E may for this purpose rise and fall by turning the fly J , whose long threaded shaft governs a forked 110 nut embracing the strap.

Fig. 10 shows an example of working the apparatus mechanically, and admits of cutting regular designs on lace, tulle, embroidery, &c., without requiring a strict superintendence, 115 quite doing away with hand-work and doing a vast amount of work.

I claim—

1. The combination of the vertically-reciprocating cutter t^5 and its blade-receiver or holding-spindle t' with the vertically-reciprocating blade-carrier r , cam g , and with the perforated collars q , slides l , and handle M , and with rollers for feeding the fabric, substantially as herein shown and described. 120

2. The cutter t^5 , combined with the spindle or blade-receiver t' , base t , stud t^2 , and vertically-reciprocating blade-carrier r , all arranged so that the cutter is swiveled in the carrier eccentrically, as specified. 125

3. The combination of the horizontal slides $l l$, which control the horizontal movements of 130

the cutter, with the sliding rack n , handle-support o' , crown-wheel o^2 , fixed rod o , and swiveled handle M , substantially as herein shown and described.

5 4. The combination of the shaft g' and its cam g with the shaft e , rollers $u v y z$, spring z' , spring-frame v' , and vertically and hori-

zontally reciprocating cutter t^5 , held in swiveled spindle or blade-receiver t' , substantially as herein shown and described.
